ABSTRACT OF THE DISCLOSURE

The casing of an electric fuse having a high interrupting capacity and a small current rating is filled with quartz sand and provided with a fusible element in the form of a cadmium wire having ends that are conductively connected by soft solder joints to the terminal caps closing the casing of the fuse. An additional heat sink is operatively related to each of said pair of caps.

BACKGROUND OF THE INVENTION

Electric fuses embodying this invention include a tubular rupturing capacity and a low current rating are generally provided with an arc-quenching filler of quartz sand and a fusible element of a metal having a relatively high resistivity and a relatively high fusing point. The fusible element supports an overlay that has a relatively low fusing point. When the latter reaches its fusing point it severs the fusible element by a metallurgical reaction in the nature of a metal diffusion process.

These prior art fuses perform satisfactorily, except that the high resistivity of their fusible element is conducive to relatively high voltage drops and relatively high $i^2 \cdot r$ losses. This is a very undesirable condition in many applications, particularly where the fuses are housed in a common enclosure together with other heat generating equipment.

Many experiments have been conducted to remove the aforementioned drawback of state-of-the-art electric high interrupting capacity fuses for low current ratings such as, for instance, fuses to be used in an electric system having a circuit voltage of 600 volts, or in excess of 600 volts, having a high available short-circuit current and which fuses have a current rating of less than 10 amps, e.g. 8 amps. These experiments consisted in combining various arc-quenching fillers and fusible elements of various metals. The outcome of these experiments was unsatisfactory to date.

SUMMARY OF INVENTION

Electric fuses that are intended to have a high interrupting capacity are provided with a tubular casing of insulating material and there is an arc-quenching filler of quartz sand inside of the casing. Both ends of the casing are closed by a pair of terminal caps mounted on the axially outer ends of the casing. A fusible normally current-carrying wire of cadmium is arranged inside the casing, submersed in the aforementioned filler of quartz sand and extends from one of the pair of terminal caps to the other of the pair of terminal caps and conductively interconnects the pair of terminal caps. Joints of a soft solder conductively connect each of the ends of said wire of cadmium to one of said pair of terminal caps.

BRIEF DESCRIPTION OF DRAWINGS

The drawings illustrate a fuse embodying this invention,

FIG. 1 being a longitudinal section taken along I—I of FIG. 2;

FIG. 2 being a transverse section taken along II—II of FIG. 1; and

2

FIG. 3 being an exploded view of the parts forming one of the ends of the fuse of FIGS. 1 and 2.

DESCRIPTION OF PREFERRED EMBODIMENT OF THE INVENTION

5 Reference numeral 1 has been applied to indicate a tubular casing of insulating material housing a pulverulent arc-quenching filler in the form of a body 2 of quartz sand. A pair of terminal caps 3 of sheet metal are mounted on the axially outer ends of casing 1 closing the latter. 10 Each terminal cap 3 has an inherent heat absorbing capacity which depends upon the particular metal it is made of, its mass, etc. The axially inner ends 3a of terminal caps 3 are crimped into casing 1 to firmly secure caps 3 to casing 1. A fusible normally current-carrying wire 4 of cadmium is arranged inside of casing 1 in coaxial relation thereto. Cadmium wire 4 is submersed in the body of quartz sand 2 and extends from one terminal cap 3 to the other terminal cap 3, thus conductively interconnecting terminal caps 3. Joints of soft solder conductively connect each of the ends of wire 4 of cadmium to one of terminal caps 3.

15 It is generally very difficult, if not impossible, to solder a wire of cadmium to a terminal cap made of thin sheet metal and having a relatively limited heat absorbing capacity. In the instant case solders having a substantially lower melting point than cadmium (which is 320.9 deg. C.) are ruled out because they are likely to melt on account of $i^2 \cdot r$ losses generated at the interfaces between the terminal caps and a fuse holder receiving the same. An acceptable solder would be 40/60 tin-lead solder having a melting point of 238 deg. C. In a soldering operation involving a terminal cap of thin sheet metal and 40/60 tin-lead solder it is normally impossible to preclude heating of the terminal cap above the melting point of the solder. 20 Because of the closeness of the melting points of cadmium and 40/60 tin-lead solder, it is normally impossible to use such solder for soldering a fusible wire of cadmium to a terminal cap of sheet metal. The cadmium wire tends to melt during the soldering operation because the terminal cap tends to exceed the melting temperature of cadmium. I have discovered that a cadmium wire can safely be soldered to a thin sheet metal terminal cap with 40/60 tin-lead solder if the cadmium wire is embedded in a body of quartz sand since the latter operates as a heat sink 25 limiting the temperature rise of the terminal cap during the soldering operation. It is, however, preferable not to rely entirely on the heat absorbing capacity of the quartz sand to preclude fusion of the cadmium wire during the process of assembly of the fuse, but to provide each of the pair of terminal caps of the fuse with an additional heat sink capable of safety limiting the ceiling temperature which each pair of terminal caps may reach during soldering operations. Such an arrangement has been shown 30 in FIGS. 1—3 of the accompanying drawing.

35 Reference character 6 has been applied to indicate a pair of heat sinks of which each is operatively related to one of terminal caps 3, and this increases the heat absorbing capacity thereof above its inherent heat absorbing capacity. Each heat sink 6 is shaped like a rivet and includes a head or rod portion 6a and a shank portion 6b. 40 Each shank portion 6b projects transversely through one of terminal caps 3 at the center thereof. The ends of cadmium wire 4 project through the same center openings or perforations in caps 3 as the shank or rod portions 6b of heat sinks 6. Each terminal cap 3 defines a recess 3b having the shape of a frustum of a cone and the head portions 6a of heat sinks 6 are arranged in recesses 3b. The axially outer ends of the cadmium wire are bent to 45 conform substantially to the shoulder formed between head portions 6a and shank portions 6b of heat sinks 6. Thus there is an immediate physical engagement between 50 55 60 65 70 75 80 85 90 95

heat sinks 6 and the axially outer ends of cadmium wire 4. The joints 5 of soft solder cover the head portions 6a of heat sinks 6 and fill the recesses 3b in caps 3. A washer 7 of asbestos fibers is interposed between each cap 3 and one of the rims of casing 1. It will be apparent from the foregoing that heat sinks 6a, 6b are bounded by caps 3, i.e. that the axially outer ends thereof do not project beyond caps 3.

There are various reasons which may cause failure of a high interrupting capacity quartz-sand-filled fuse. One of these possible reasons is the generation of excessive arc energy under major fault current conditions. Another possible reason is formation of a fulgurite during the process of reducing a major fault current to zero whose dielectric strength is insufficient and that breaks down under the action of the recovery voltage. Still another possible reason which may cause failure of a high interrupting capacity quartz-sand-filled fuse is excessive heating of the quartz sand prior to kindling of an arc in the fuse. This kind of failure may occur at small current intensities barely exceeding the minimum fusing current. High interrupting capacity fuses having a fusible element whose resistance and whose $i^2 \cdot r$ losses are relatively large when carrying the rated current, or the minimum fusing current, are particularly susceptible to failure on account of excessive heating of the quartz sand prior to kindling of an arc inside of the fuse.

Considering a current having an A-C voltage whose R.M.S. value is E , whose self-inductance is L , whose external resistance is R , and that includes a fuse whose fusible element has a resistance r , the following equation obtains for the R.M.S. value of the current I .

$$I = \frac{E}{(R+r)^2 + (\omega L)^2} \quad (1)$$

The increase in temperature ϑ of a fusible wire carrying an electric current depends upon its volume v , the specific heat of the material of which the wire is made, the surface o of the wire and a coefficient ξ of heat transmission. The following equation interrelates these quantities:

$$\gamma \cdot v \cdot \frac{d\vartheta}{dt} + \xi \cdot o \cdot \vartheta = I^2 r$$

$$= \frac{E^2 \cdot r}{(R+r)^2 + (\omega L)^2} \quad (2)$$

The first term in this equation refers to heat generated inside the fuse and the second term refers to heat dissipated from the fuse.

The resistance r of the fusible wire depends, on the other hand, on its temperature, as is apparent from the following equation.

$$r = r_0 (1 + \alpha \vartheta) \quad (3)$$

wherein r_0 is the resistance of the fusible wire at room temperature and wherein α is the temperature coefficient of resistance.

It is apparent from the above that establishing a general solution of Equation 2 is a rather complex matter. The data included in the following table and their following discussion are conductive to an appreciation of the present invention without an elaborate mathematical treatment of the physics thereof.

Every fusible wire carrying a current sufficiently high to cause ultimate melting of the wire undergoes a first heating period during which its temperature is raised to the wire's fusing point. The lower the fusing point, the lower the temperature to which the surrounding quartz sand tends to be raised during this first heating period. The first heating period is followed by a period during which the temperature of the fusible wire remains unchanged and the fusible wire is liquefied. The temperature rise of the quartz sand filler during this period tends to be relatively low if the heat of fusion of the wire metal is relatively low. If the liquefied wire is not severed by external forces, the temperature of the liquefied metal increases from its melting point to its vaporizing point. The temperature increase of the surrounding quartz filler during this second heating period tends to be relatively limited if the difference between the boiling point and the melting point of the metal of which the wire is made is relatively limited. During vaporization of the fusible wire its temperature remains unchanged until the liquid current path is broken, and an arc is kindled.

The good performance at low current levels of quartz-sand-filled high interrupting capacity fuses having a fusible element in form of a cadmium wire may be attributed mainly to the relatively low fusing point of cadmium (320.9 deg. C.), the relatively low latent heat of fusion (13 cal./gram) of cadmium, and the relatively low difference (416.1 deg. C.) between the melting point and the boiling point of cadmium.

Zinc, lead and tin wires have been tried in combination with quartz sand fillers and the performance of such fuses at low current intensities has been found to be lacking, or unsatisfactory.

It will be understood that I have illustrated and described herein a preferred embodiment of my invention, and that various alterations may be made in the details thereof without departing from the spirit and scope of the invention as defined in the appended claims.

I claim.

1. An electric high interrupting capacity fuse for low current ratings including in combination:
  - (a) a tubular casing of insulating material;
  - (b) an arc-quenching filler of quartz sand inside said casing;
  - (c) a pair of knife-contactless terminal caps mounted on the axially outer ends of said casing and closing said casing, each of said pair of terminal caps having an inherent heat absorbing capacity;
  - (d) fusible wire of cadmium arranged inside of said casing, submersed in said filler of quartz sand and extending from one of said pair of terminal caps to the other of said pair of terminal caps and conductively interconnecting said pair of terminal caps;
  - (e) a pair of joints of soft solder each conductively connecting one of the ends of said wire of cadmium to one of said pair of terminal caps; and
  - (f) a pair of heat sinks each on one of said pair of terminal caps each in addition to one of said pair of joints of soft solder to increase the heat absorbing capacity of each of said pair of terminal caps beyond said inherent heat absorbing capacity thereof to safely limit the ceiling temperature which each of

said pair of terminal caps may reach during soldering operations.

2. An electric high interrupting capacity fuse as specified in claim 1 wherein said joints of soft solder are of 40/60 tin-lead solder.

3. An electric high interrupting capacity fuse as specified in claim 1 wherein said heat sink includes a head portion situated on the outer surface of one of said pair of terminal caps and a shank portion projecting transversely through one of said pair of terminal caps at the center thereof, said fusible wire having ends projecting transversely through each of said pair of terminal caps at the center thereof and being bent to conform substantially to the shoulder formed between said head portion and said shank portion of said heat sink, each of said joints of soft solder covering said head portion of said heat sink of one of said pair of terminal caps.

4. An electric high interrupting capacity fuse as specified in claim 3 wherein each of said pair of terminal caps defines a recess having the shape of a frustum of a cone, and wherein said head portion of said heat sink of each of said pair of caps is arranged in said recess thereof.

5. An electric high interrupting capacity fuse for low current ratings including in combination:

- (a) a tubular casing of insulating material;
- (b) a pair of blade-contactless terminal caps mounted on the axially outer ends of said casing and closing said casing, each of said pair of terminal caps having a recessed portion in the form of a frustum of a cone forming the axially outer end surface thereof and said recessed portion of each of said pair of terminal caps defining a perforation in the center thereof;
- (c) a fusible wire of cadmium arranged inside said casing extending from one of said pair of terminal caps to the other of said pair of terminal caps and conductively interconnecting said pair of terminal caps, said wire of cadmium having axially outer ends each projecting into said recessed portion of one of said pair of terminal caps through said perforation in the center thereof;
- (d) an arc-quenching filler of quartz sand inside said casing submersing said wire of cadmium, said quartz sand being capable of exerting an intense action of heat dissipation away from said wire of cadmium while said wire of cadmium is still intact;
- (e) a pair of heat sinks substantially in the shape of short rods each arranged inside said recessed portion of one of said pair of terminal caps, each of said pair of heat sinks being confined to said recessed portion of one of said pair of terminal caps and each of said pair of heat sinks having an axially inner end projecting through said perforation in the center of said recessed portion of one of said pair of terminal caps and in physical engagement with one of the axially outer ends of said wire of cadmium; and
- (f) a pair of joints of soft solder each in said recessed portion of one of said pair of terminal caps and each in physical engagement with one of said pair of

terminal caps, one of the axially outer ends of said wire of cadmium and one of said pair of heat sinks.

6. An electric high interrupting capacity fuse for low current ratings including in combination:

- (a) a tubular casing of insulating material;
- (b) an arc-quenching filler of quartz sand inside said casing;
- (c) a pair of terminal caps mounted on the axially outer ends of said casing, closing said casing and each having an inherent heat absorbing capacity, each of said pair of terminal caps further having a recessed portion in the form of a frustum of a cone forming the axially outer end surface thereof and said recessed portion of each of said pair of terminal caps defining a perforation in the center thereof;
- (d) a fusible wire of cadmium arranged inside said casing, submersed in said filler of quartz sand, extending from one of said pair of terminal caps to the other of said pair of terminal caps and conductively interconnecting said pair of terminal caps, said wire of cadmium having axially outer ends each projecting into said recessed portion of one of said pair of terminal caps through said perforation in the center thereof;
- (e) said recessed portion of each of said pair of terminal caps being filled with a mass of 40/60 tin-lead solder conductively connecting each of the ends of said wire of cadmium to one of said pair of terminal caps; and
- (f) a pair of substantially rod-shaped heat sinks each having an axially outer end confined to the space of said recessed portion of one of said pair of terminal caps and each having an axially inner end projecting out of said recessed portion of one of said pair of terminal caps through said perforation in the center thereof, each of said pair of heat sinks being substantially submersed in said mass of 40/60 tin-lead solder in said recessed portion of each of said pair of terminal caps, and each of said pair of heat sinks increasing the heat absorbing capacity of one of said pair of terminal caps above said inherent heat absorbing capacity thereof to safely limit the ceiling temperature which each of said pair of terminal caps may reach when said recess in each of said pair of terminal caps is being filled with said 40/60 tin-lead solder.
